UNITED STATES PATENT OFFICE.

DANIEL HALLY-SMITH, OF PARIS, FRANCE, ASSIGNOR TO LYMEOGENE, OF PARIS, FRANCE, A LIMITED LIABILITY COMPANY OF FRANCE.

DESIGN FOR A BOTTLE.

Application filed September 7, 1927, Serial No. 23,313, and in France November 25, 1926. Term of patent 14 years.

To all whom it may concern:

Be it known that I, DANIEL HALLY-SMITH, citizen of the United States of America, and resident of Paris, Seine, France, whose post-office address is 22 Place Vendome, Paris, Seine, France, have invented a new, original, and ornamental Design for a Bottle, of which the following is a

specification, reference being had to the accompanying drawing, forming part thereof.

The figure is a view in elevation of a bottle, showing my new design.

I claim:

The ornamental design for a bottle substantially as shown.

DANIEL HALLY-SMITH.
